United States Patent Office.

H. C. GRIFFIN, OF FRANKLIN, NEW HAMPSHIRE.

Letters Patent No. 65,376, dated June 4, 1867.

MAGIC ARROW TOY.

The Schedule referred to in these Letters Patent and making part of the same.

TO ALL WHOM IT MAY CONCERN:

Be it known that I, H. C. GRIFFIN, of Franklin, in the county of Merrimack, and State of New Hampshire, have invented a new and amusing toy for children, which I term the Magic Arrow; and I do hereby declare that the following is a full, clear, and exact description thereof, which will enable others skilled in the art to make and use the same, reference being had to the accompanying drawings, forming part of this specification, in which—

Figure 1 is a perspective view of the invention, showing the manner in which it is used.

Figure 2, a view of the portion of the arrow which is hidden by the hand of the operator in fig. 2.

Similar letters of reference indicate like parts.

This invention relates to a simple toy for children, designed to supersede the ordinary bow and arrow, and it consists of an elastic cord constructed of India rubber or other suitable elastic material, and having its ends connected to the prongs of a forked bar, and an arrow provided with a slit near its head to receive the elastic cord, which, by drawing back the arrow, is stretched or distended, so as to propel the arrow a considerable distance when the same is released.

A represents a bar of metal or wood having two prongs *a a* to which the ends of an elastic cord, B, are attached. This cord may be constructed of any suitable elastic material; India rubber would probably answer the best purpose. C is an arrow, which may be constructed of wood of any suitable length, and made thicker at one end than at the other to form a head, *b*. This arrow is notched at the inner part of its head to receive the elastic cord B, as shown clearly in fig. 1 at *c*; and it will be seen that the operator, by holding the bar A in one hand and drawing back the arrow C with the other in the direction indicated by arrow 1, the cord B will be stretched and distended, and by relaxing the hold on the arrow, the cord B, in suddenly assuming its normal condition, will propel the arrow forward.

This toy may be manufactured at a small cost, and is preferable to a bow and arrow for small children.

What I claim as new, and desire to secure by Letters Patent, is—

The elastic cord B, attached to a forked or other suitable bar A, and the notched arrow C all arranged substantially as and for the purpose specified.

H. C. GRIFFIN.
